SHOE MACHINE

Israel I. Hersey, Beverly, Mass., assignor to United
Shoe Machinery Corporation, Flemington, N. J.,
a corporation of New Jersey

Application May 15, 1946; Serial No. 669,815

9 Claims. (Cl. 112—35)

1

The present invention relates to improvements in shoe machines, and more particularly to a machine for sewing the inseam and for trimming the sewn inseam of a shoe.

It is a principal object of the invention to provide a shoe machine which will be of relatively simple and compact construction, and will operate in a satisfactory manner for the performance of an inseam sewing operation upon a shoe, and for the trimming of the sewn inseam in a single operation about the sole margin of the shoe.

It is another object of the invention to provide a shoe machine of this general description having mechanisms for sewing and for trimming the sewn inseam in which the operation of sewing the inseam will be completed so that those portions of the upper, inseam and welt included in the stitch will be drawn firmly together and set before the trimming operation takes place.

It is another object of the invention to provide in a shoe machine of this general description, a construction and arrangement of the inseam sewing and trimming instrumentalities in which these mechanisms are located with relation to one another for the performance of their respective functions at closely adjacent points in the line of feed.

It is another object of the invention to provide in a machine of this general description, work supporting and guiding means adapted for the assistance of the operator to maintain the shoe in the proper relation to each of the inseam sewing and inseam trimming mechanisms spaced a substantial distance from one another along the line of feed as the point of operation is transferred about the margin of the shoe sole.

With these and other objects in view as may hereinafter appear, a feature of the invention consists in the provision of a shoe machine having a sewing mechanism for sewing an inseam, an inseam trimming mechanism spaced from the sewing mechanism in the line of feed for trimming a portion of the inseam comprised by portions of the channel lip or rib, upper and welt which have been drawn firmly together and set by previously completed stitches of the seam, and work feeding and guiding devices adapted for the assistance of the operator to maintain the shoe in the proper relation to each of the inseam sewing and inseam trimming mechanisms and to transfer the point of operations about the sole margin of the shoe.

Another feature of the invention consists in the provision of an oscillatory trimming knife which is arranged to move transversely across

2

the inseam to trim that portion of the inseam drawn in and held by the last completed stitch, and which is mounted for this purpose at that side of the needle with the completed stitches of the seam to move as a unit therewith.

Another feature of the invention consists in the provision of an anvil member which serves to support the inseam against the thrust of the knife, is provided with a downwardly extending post which tracks in the bottom of the stitch receiving channel to locate the sewn portion of the inseam accurately with relation to the trimming knife, and with a projecting arm which extends substantially across the plane of operation of the needle and above the path of the needle to serve as a stationary thread finger to provide a more accurate control of the thread during the needle threading or looping operation and during the movement of the movable thread finger to give up slack thread to the needle during its loop drawing stroke.

The several features of the invention consist also in the devices, combinations and arrangement of parts hereinafter described and claimed which, together with the advantages to be obtained thereby, will be readily understood by one skilled in the art from the following description taken in connection with the accompanying drawings, in which

Fig. 1 is a view in right side elevation illustrating a portion of the sewing head of an inseam shoe sewing machine, only so much of the machine having been disclosed as is believed necessary to illustrate the connections of the present invention therewith;

Fig. 2 is a detail view in front elevation, partly in section, illustrating particularly the sewing and work guiding devices;

Fig. 3 is a view in right side elevation of the parts shown in Fig. 2;

Fig. 4 is a view similar to Fig. 2, but with the parts in a different position, in which the thread finger is retracted to the limit of its bight forming stroke; and

Fig. 5 is a view in right side elevation of the parts in the position shown in Fig. 4.

The machine disclosed in the drawings as illustrating in a preferred form the several features of the present invention, comprises a welt sewing machine for attaching the welt to the insole and associated upper of a shoe mounted on a last, and is substantially identical in its construction and mode of operation with the machine disclosed in United States Letters Patent to Epler No. 1,108,560, granted August 25, 1914. The

shoe sewing mechanism of the machine comprises a curved hook needle 20, a needle guide 22, a looper 24, a take-up 26, an auxiliary take-up 28 and a thread finger 30 movable to supply slack thread to the needle, together with a back rest 32 and a welt guide 34 for supporting and guiding the work with relation to the sewing mechanism.

In accordance with the present invention, there is also provided an inseam trimming mechanism which is constructed and arranged to trim a sewn portion of the inseam comprised by the channel lip of the insole, the upper and welt, which have been drawn firmly together and set by the completed stitches of the seam.

In accordance with the usual construction of inseam sewing machines of the type illustrated, the needle 20 is mounted on a needle segment 44 mounted to turn on a stationary bearing and externally supported in a raceway 46 on the machine frame. In the illustrated machine, the awl has been omitted. The channel guide 36 is movable in the line of feed to feed the work, and to this end is mounted on a feed slide generally indicated at 48 which is reciprocated in the line of feed by means of a cam actuated feed lever 50. The feed lever 50 is supported at its forward end to turn about a fixed pivot and is connected to move the feed slide through connections including a block 52 adjustably supported in a slotted portion of the lever 50 and arranged to engage in a guideway 54 formed in the bottom side of the feed slide 48. The needle segment 44 is actuated from the reciprocable needle lever generally indicated at 60 (Fig. 1) which is connected by means of a curved link 62 to a pivot pin 64 on the needle segment 44. The needle guide 22 is mounted on a pivot pin 65 to turn coaxially with the needle segment 44, and is positively actuated through connections which include a gear segment 66 rigidly secured to the pin 65, and a cam actuated lever 68 supported to turn on a pivot 70, and having formed at its forward end a gear segment 72 which meshes with the segment 66.

The thread finger 30 is pivotally supported for movement rearwardly to engage with and form a bight in the thread extending from the looper to the work, and then forwardly to give up the slack thread thus provided to the needle during its retracting stroke. The main take-up of the machine is of usual construction consisting of the take-up lever 26 which is cam actuated and has mounted thereon a thread truck 76. The auxiliary take-up consists of the auxiliary take-up lever 28 having a thread truck 78 mounted thereon. The auxiliary take-up lever 28 is pressed upon by a spring actuated plunger 80. This plunger is mounted in a vertical guideway in the frame of the machine, and its upper end is acted upon by a coil spring 82 seated in a recess in the machine frame. The auxiliary take-up is thus spring pressed, its upward movements being resisted by the tension of the spring 82. The thread indicated at 84, after passing over the tension wheel at the rear of the machine, passes over a guide truck 86, then under the truck 78 of the auxiliary take-up, and then over the truck 76 of the main take-up. The arrangement of these trucks is such that during the rising movement of the main take-up, the auxiliary take-up is moved upward, and during the falling movement of the main take-up, the auxiliary take-up is allowed to fall and maintain a tension on the thread determined by the strength of the spring

82 and the relative positions of the three trucks. The main take-up falls during the thread pulling movement to to the thread finger, during the looping movements of the looper, and during the retracting stroke of the needle. In accordance with the usual practice to prevent the auxiliary take-up from stealing thread from the thread finger 30 during its loop delivery or forward stroke, and while the needle is making the first part of its retracting stroke, a stop 88 is provided to limit the forward movement of the auxiliary take-up, which stop is engaged by an adjustable abutment screw 90 mounted in the auxiliary take-up lever 28. The stop 88 and abutment screw 90 are so arranged with relation to the falling movement of the take-up and the thread delivering stroke of the thread finger, that the falling movement of the auxiliary take-up must stop before the thread finger 30 begins its thread delivering stroke. Inasmuch as the construction and arrangement of the thread handling instrumentalities thus far described are substantially that illustrated in the Eppler patent above referred to, no further description or illustration thereof is believed necessary.

In accordance with the invention, an inseam trimming mechanism is provided which comprises an inseam trimming knife 96 secured in a curved guideway 97 formed integrally with the needle segment 44. The knife 96 is located at the left side of the needle with the completed stitches of the seam, and is spaced therefrom to cause the knife to trim a portion of the inseam held together by the last completed stitch of the seam. The knife is supported to turn about the same center with the needle, but on a shorter radius, so that it passes transversely across the seam above the line of stitching. The cutting edge of the knife 96 is set at an angle to cause the knife to make a shearing cut.

Further in accordance with the invention, there is provided an anvil member 98 which rides in the stitch receiving channel and is arranged to support the sewn inseam against the thrust of the knife 96. The anvil member 98 comprises an arm extending lengthwise of the line of feed and with the shank portion 100 thereof located at that side of the sewing point toward the completed stitches of the seam. The upper edge of the anvil member is shaped to provide a cooperating shearing edge with relation to which the knife acts.

The anvil member 98 has formed on the under side thereof a downwardly extending foot or post 102 which rides in the base of the stitch receiving channel and serves to locate that portion of the shoe being operated upon accurately with relation to the inseam trimming knife.

The anvil member 98 is further constructed and arranged to assist in the control of the thread by the thread handling devices, being provided with an extension 104 along the stitch receiving channel passing substantially across the plane of operation of the needle and above the path of movement of the needle. The extension 104 serves as a stationary thread finger which cooperates specifically with the movable thread finger 30 to maintain an accurate control of the thread during the stitch forming operation which will with certainty prevent the thread from following into the path of movement of the inseam trimming knife 96.

As best shown in Figs. 1 and 2 of the drawings, the anvil member 98 is secured by means of screws 112 to a support 114 which is mounted for for-

ward and back adjustment upon a slideway 116 formed in the under side of a U-shaped bracket 118. A clamping screw 120 which extends through a slot 122 in the support 114 and is screw-threaded in the bracket 118 serves to secure the support 114 into the bracket 118 in the desired adjustment. The U-shaped bracket 118 is pivotally mounted on a bushing 124, and is rigidly clamped in the desired position of angular adjustment with relation thereto, by means of a clamping screw 126 which passes through the two arms of the U-shaped bracket and through an axial bore in the bushing 124. The bushing 124 is carried in a bearing formed in a bracket 128 which is secured by means of screws 130 to the front side of the sewing head 132. In order to provide an additional adjustment of the anvil member 98 lengthwise of the stitch receiving channel, the bushing 124 is arranged for axial adjustment in its bearing, and is clamped rigidly in position by means of a clamping pin 134 having one side flattened at 136 for engagement with a corresponding flat 138 in the bushing 124. The engaging flattened portions 136, 138 serve to key the bushing 124 against rotational movement in its bearing while permitting axial adjustment thereof. A nut 140 screw-threaded to the clamping pin 134 serves to clamp the bushing 124 rigidly in adjusted position.

In the operation of the machine, the shoe is guided and advanced in the usual manner with relation to the sewing mechanism, being supported against the back rest 32 and welt guide 34 and being further controlled by the channel guide 36 to which is imparted a reciprocating movement to feed the shoe. In the illustrated embodiment of the invention, the shoe is further guided and located by means of the post 102 of the anvil member 98 which tracks in the stitch receiving channel and further functions to locate that portion of the sole margin of the shoe at which the inseam trimming operation upon the sewn inseam is being performed. During the operation of the illustrated machine, the shoe is therefore supported and guided with respect to the operating devices at two separated points along the margin of the shoe sole. The second point of support of the shoe with respect to the inseam trimming knife is of substantial assistance to the operator to maintain the shoe in its proper operating relation to each of the sewing and inseam trimming mechanisms as the operation is transferred about the sole margin of the shoe. The anvil member 98, also, provides support for the shoe against the thrust of the knife which would otherwise tend to swing the shoe out of position about a fulcrum provided by the engagement of the channel guide with the stitch receiving channel.

As will be evident from an inspection of the drawings, the inseam trimming knife acts to trim that portion of the sewn inseam held together by the last completed stitch of the seam, the operation of the knife being timed with the advancing movement of the needle to trim the inseam only after the previous stitch has been finally drawn in and after the work has been fed preparatory for the advancing movement of the needle to receive and to draw a new loop of thread through the work.

During the stitch forming operation, the thread handling devices, including particularly the anvil member 98, act to support and to control the movement of the thread so that the possibility of

interference or severing of the thread by the knife is substantially eliminated. After the work has been fed by the action of the channel guide, and the needle starts downwardly through the work, the take-up 26 moves upwardly to its limiting raised position to pull in the previously formed loop against the shank of the needle and to draw off additional thread from the supply. The auxiliary take-up 28 is simultaneously moved upwardly by the tension on the thread against the pressure of its spring. Thereafter, the take-up starts its downward movement giving up thread first to the thread finger and looper, and then to the needle as it is withdrawn through the work. The movable thread finger 30 starts to move rearwardly from the position shown in Fig. 3 to draw a bight of slack thread before the needle and inseam trimming knife associated therewith have completed their work piercing movements. The anvil member 98 is particularly constructed and arranged to support the thread in position for the most efficient operation of the thread handling devices, and away from the path of movement of the inseam trimming knife. During the rearward thread drawing movement and subsequent forward thread giving movement of the thread finger 30, both legs of the bight of thread held by the thread finger are engaged around the extension 104 of the anvil member 98, so that the lengths of thread extending from the previously formed stitch in the seam, and from the needle as it is drawn into the work are at all times guided directly away from the sewing rib and away from the path of movement of the inseam trimming knife 96. During the continued retracting movement of the needle, the thread finger 30 is returned to its initial position shown in Fig. 3 and the thread released therefrom, still guided by the finger projection 104, is drawn down tightly into the base of the stitch receiving channel to draw in the stitch holding together the parts of the inseam which will then be trimmed off by the knife 96 during the next advancing movement of the needle.

It will be understood that the invention is not limited to the specific embodiment shown, and that various deviations may be made therefrom without departing from the spirit and scope of the appended claims.

What is claimed is:

1. An inseam chainstitch shoe sewing machine having, in combination, mechanism for sewing the inseam of a welted shoe including a curved hook needle, and an inseam trimming knife supported to move as a unit with the needle and spaced therefrom at that side of the needle with the completed stitches of the seam to trim surplus stock from a sewn portion of the inseam.
2. An inseam chainstitch shoe sewing machine having, in combination, a curved hook needle, a looper, a thread finger movable to supply slack thread to the needle, and an inseam trimming knife arranged for oscillatory movement transversely across the line of stitching and located at that side of the needle with the completed stitches of the seam to trim that portion of the inseam held together by the last completed stitch.
3. An inseam chainstitch shoe sewing machine having, in combination, sewing mechanism comprising a curved hook needle, a looper, a thread finger movable to supply slack thread to the needle, and an inseam trimming mechanism arranged at that side of the needle with the completed stitches of the seam, said trimming mecha-

nism comprising a knife edge arranged for oscillatory movement transversely across the line of stitching for trimming the sewn inseam, and means for guiding the shoe with relation to each of said sewing and trimming mechanisms.

4. An inseam chainstitch shoe sewing machine for sewing together associated shoe parts including the insole arranged to provide a sewing rib with a stitch receiving channel at the base thereof in the insole having, in combination, a curved hook needle, a looper, a thread finger movable to supply slack thread to the needle, and an inseam trimming mechanism arranged at that side of the needle with the completed stitches of the seam to trim the sewn inseam, said trimming mechanism comprising a knife edge moving transversely across the line of stitching, and an anvil in the stitch receiving channel for supporting the sewing rib against the thrust of the knife.

5. An inseam chainstitch shoe sewing machine for sewing together associated shoe parts including the insole arranged to provide a sewing rib with a stitch receiving channel at the base thereof in the insole having, in combination, a curved hook needle, a looper, a thread finger movable to supply slack thread to the needle, and an inseam trimming mechanism arranged at that side of the needle with the completed stitches of the seam to trim the sewn inseam, said trimming mechanism comprising a knife supported to move as a unit with the needle, and spaced therefrom at that side of the needle with the completed stitches of the seam, and an anvil in the stitch receiving channel for supporting the sewing rib against the thrust of the knife.

6. In an inseam chainstitch shoe sewing machine, the combination of a curved hook needle, a looper, a thread finger movable to supply slack thread to the needle, an inseam trimming knife supported to move as a unit with the needle, and spaced therefrom to trim the sewn portion of the inseam, and an anvil comprising a downwardly extending channel engaging post, a shearing surface over which the knife passes, and a thread engaging arm extending substantially across the plane of operation of the needle and above the path of needle movement.

7. In an inseam chainstitch shoe sewing machine, the combination of a curved hook needle, a looper, a thread finger movable to supply slack thread to the needle, an inseam trimming knife supported to move as a unit with the needle, and spaced therefrom to trim the sewn portion of the

inseam, and an anvil comprising a shearing surface over which the knife passes, and a thread engaging arm for positioning the portion of the thread extending between the needle and the thread finger during the loop drawing stroke of the needle.

8. An inseam chainstitch shoe sewing machine for sewing together associated shoe parts including the insole arranged to provide a sewing rib with a stitch receiving channel at the base thereof in the insole having, in combination, sewing mechanism including a curved hook needle, a thread finger movable to supply slack thread to the needle, an inseam trimming mechanism comprising a trimming knife located at that side of the needle with the completed stitches of the seam for trimming the sewn inseam, a channel guide for guiding the shoe with relation to the sewing mechanism, and a separate guide engaging in said stitch receiving channel adjacent the point of operation of said trimming knife upon the sewn inseam.

9. An inseam chainstitch shoe sewing machine for sewing together associated shoe parts including the insole arranged to provide a sewing rib with a stitch receiving channel at the base thereof in the insole having, in combination, sewing mechanism including a curved hook needle, a thread finger movable to supply slack thread to the needle, a channel guide, an inseam trimming mechanism comprising a knife edge moving transversely across the line of stitching, and located at that side of the needle with the completed portions of the seam for trimming the completed portions of the inseam, an anvil engaging in said stitch receiving channel adjacent the point of operation of the trimming knife edge upon the sewn inseam for supporting the sewing rib against the thrust of the knife edge, and supporting means for said anvil adjustable in a plurality of planes for adjusting the position of the anvil.
